UNITED STATES PATENT OFFICE.

CASPER CHRISTOPHERSON, OF MUKILTEO, WASHINGTON.

AUXILIARY CAR-STEPS.

1,261,489.

Specification of Letters Patent.

Patented Apr. 2, 1918.

Application filed July 13, 1917. Serial No. 180,410.

To all whom it may concern:

Be it known that I, CASPER CHRISTOPHERSON, a citizen of the United States, residing at Mukilteo, in the county of Snohomish 5 and State of Washington, have invented certain new and useful Improvements in Auxiliary Car-Steps; and I do hereby declare the following to be a full, clear, and exact description of the invention, such as will 10 enable others skilled in the art to which it appertains to make and use the same.

The object of this invention is to associate, in a novel manner, with the fixed steps of a car, foldable auxiliary steps that can 15 be moved in an expeditious and convenient manner to operative or inoperative position, the said auxiliary steps being adapted when in operative position to extend beyond the lower end of the fixed steps of the car and 20 of such construction as to be capable of supporting considerable weight.

Other objects will appear and be better understood from that embodiment of my 25 invention of which the following is a specification, reference being had to the accompanying drawings, in which:

Figure 1 is a perspective view of the fixed steps of a car with the auxiliary steps associated therewith, showing the latter in operative position.

Fig. 2 is a section taken on the line 2—2 of Fig. 1.

Fig. 3 is a longitudinal sectional view taken through the fixed car steps and auxiliary steps with the latter in folded position.

Fig. 4 is a fragmentary front elevation of the fixed car steps showing the guides in position.

Fig. 5 is a section on the line 5—5 of Fig. 4.

Fig. 6 is a detail section on the line 6—6 of Fig. 5.

Referring to the drawings in detail, the 45 fixed steps of the car are shown as including a pair of side members 1 that are connected by the treads 2 and risers 3, the risers being disposed inwardly of the outer longitudinal edges of the treads 2 to provide 50 overhanging ledges, as shown in Fig. 2 of the drawings.

Movably associated with the fixed car steps, at the lower end thereof, are the auxiliary steps, designated as an entirety 55 by the numeral 4, and which comprises a pair of metallic supporting rails 5—5, each

of which is bent to provide a plurality of pairs of opposed spaced horizontal portions 6, the pairs of opposed horizontal portions being disposed in offset relation one above 60 the other. The uppermost pair of horizontal portions 6 overlie and rest upon the lowermost tread of the fixed step when the auxiliary steps are in operative position, and the other pairs of opposed horizontal portions 65 form supports for treads 7 that lie in offset planes below the lowermost tread of the fixed steps, when the auxiliary steps are in operative position. The rails 5 have their upper ends bent upwardly from the uppermost pair of opposed horizontal portions 6 and then deflected laterally in opposite directions, as shown at 8.

Mounted on the inner side of the side members 1 of the fixed steps, and at opposite points, are guides 9, each of which is formed of a pair of spaced sections, the opposed faces of which are grooved, as shown at 12 in Fig. 6 of the drawings. Projecting laterally from the outer side edges of the 80 deflected upper ends 8 of the side rails are fingers 11, which have their outer ends bent at right angles, as shown at 12, and extended between the sections forming the respective guides 9, and the free terminals 85 of the angular portions 12 have secured thereto spherical shaped heads 13, which are slidably received by the grooves in the opposed faces of the sections forming the respective guides 9. When the auxiliary 90 steps are in operative position, the fingers 11 are located at the inner ends of the guides 9, and the free terminals of the deflected ends 8 of the supporting rails 5 are engaged beneath the outer longitudinal edge of the 95 adjacent uppermost tread 2 of the fixed steps. When it is desired to move the auxiliary steps to inoperative position, the steps are slid outwardly so as to withdraw the deflected ends 8 of the supporting rails 5 from 100 beneath the adjacent uppermost tread 2, and the outward movement of the steps are continued until the fingers 11 are located at the outer ends of the guides 9. The outer ends of the auxiliary steps are then raised 105 vertically, the spherical heads serving as fulcrums for the auxiliary steps, and the steps are then moved to the position shown in Fig. 3 of the drawings.

It is evident that various changes might 110 be resorted to in the form, construction and arrangement of the several parts with-

out departing from the spirit and scope of the invention as claimed.

What I claim is:

1. The combination with the fixed car steps having stationary guides mounted thereon and positioned above the lowermost tread of the steps of auxiliary steps including a pair of supporting rails and treads mounted thereon, spherical heads formed on said rails and mounted in said guide-ways for rotary and sliding movement, as and for the purpose specified.

5 2. The combination with the fixed car steps, of auxiliary car steps including rigid supporting rails bent to provide a series of tread supporting portions, spherical heads formed on the upper terminals of the rails, rigid guide ways mounted on the fixed car steps above the first treads, said spherical heads being positioned in the guide ways and sliding and rotary movement, as and for the purpose specified.

10 3. The combination with the fixed car

steps of auxiliary steps slidably and rotatably associated with said steps and including a pair of supporting rails bent to provide pairs of opposed horizontal portions arranged in offset relation one above the other, the uppermost pair of horizontal portions being adapted to rest on the lowermost tread of the fixed car steps when the auxiliary steps are in operative position, treads supported by the other pairs of horizontal portions, and vertically disposed elements extending above the uppermost pair of horizontal portions and adapted to terminally engage under the adjacent uppermost tread when the auxiliary steps are in operative position.

25 30 35 In testimony whereof I affix my signature 40 in presence of two witnesses.

CASPER CHRISTOPHERSON.
